TOY AERIAL BOMB

Carlos A. Ramirez, College Park, Ga.

Application October 23, 1945, Serial No. 624,041

4 Claims.

(Cl. 46—200)

1 This invention relates to new and useful improvements in toy war equipment and more particularly to a toy aerial bomb which in use will be quite realistic in effecting a detonation and apparent devastation of toy buildings, soldiers, etc.

The principal object of the present invention is to provide an aerial bomb which can be dropped by contestants amidst their toy soldiers and concentrations of toy buildings and other objects, which is so constructed that when it strikes an object a detonation occurs and simultaneously a mechanism of the toy bomb is released to effect a sweeping action of a pre-wound spring element knocking over everything within range.

Another important object of the invention is to provide a toy aerial bomb which while being realistic in its actions is definitely safe to play with by children.

Other objects and advantages of the invention will become apparent to the reader of the following specification.

In the drawings:

Figure 1 represents a perspective view of the toy bomb with the spring sweeper shown in broken lines.

Figure 2 is a perspective view showing the toy bomb inserted into the winding block and with the spring almost completely wound.

Figure 3 is a perspective view of the toy bomb and winding block with the spring fully wound and about to be held by the lug.

Figure 4 is a side elevational view of the toy bomb in upright position with a portion in section to disclose the engagement of the lug with the spring end.

Figure 5 is an end elevational view with the latch in open position and showing a bomb having been rotated from the position shown in Figure 3 left and with the lug projected to engage behind the offset end of the spring.

Figure 6 is a fragmentary sectional view through the winding block.

Figure 7 is a cross sectional view taken substantially on the line 7—7 of Figure 4.

Figure 8 is a transverse sectional view taken substantially on the line 8—8 of Figure 4.

Referring to the drawings wherein like numerals designate like parts, it can be seen that numeral 5 denotes a body of ovate elongated and stream-lined construction, having at its reduced end portion a plurality of radially disposed fins 6. Extending inwardly from the enlarged end of the body 5 is a longitudinally extending bore 7 merging with a pocket 8 which opens through

2 one side portion of the body 5. This pocket 8 is narrow and extends upwardly to merge with a short circumferentially extending slot 9. A tack or the like 10 having a head is driven into the upper wall of this slot 9 and this slot 9 defines a cap receiving chamber. Any flat detonating cap will be suitable.

A plunger rod 11 is slideable in the bore 7 and provided with a suction cup 12 at its lower end. The upper or inner end of this rod 11 is provided with a laterally disposed striker 13 terminating in a lug 14 at the outside of the body 5. This striker 13 projects laterally through the pocket 8 to the outside of the body 5 as shown.

15 Just below the pocket 8 the body 5 is provided with a circumferentially extending groove 15 in which is wound an elongated strip spring 16, the inner end of which is anchored to the body 5. The outer end of the spring is provided with a laterally disposed or offset roll 17 against which the lug 14 can be disposed when the spring is to be held in wound position.

In the use of the aerial bomb, a block 18 is employed in winding the spring 16. This block 18 has a bore 19 therethrough and the wall of this block at one end thereof has a passageway 20 therethrough and through which the spring 16 can feed when being wound in the groove 15. Adjacent the passageway 20 is a pocket 21 in the wall of the bore 19 which opens through the same end of the block as the passageway 20. On the end of the block 18 through which the passageway 20 and pocket 21 open, an arcuate-shaped closure 22 is provided and pivotally secured as at 23 to the block. This closure is capable of being swung over the open sides of the passageway 20 and pocket 21 to prevent displacement of the spring as it is being wound onto the body 5.

As shown in Figure 2, by holding the block 18 and rotating the bomb body 5 to the left, the spring strip 16 is wound onto the body 5 and when the offset roll 17 of the spring 16 is seated in the passageway 20, the closure 22 can be swung outwardly, exposing the passageway 20 and pocket 21. The body 5 can now be rotated, as for instance, to the left in Figure 3, so as to bring the lug 14 into registered relation with the pocket 21, whereupon the lug 14 is forced into the pocket 21 which, of course, moves the plunger rod 11 and cap 12 outwardly into set position. The winding block 18 may now be slipped off of the body 5, a cap such as is used in toy pistols is then introduced into the slot 9 and the toy bomb is ready for use.

55 The bomb is dropped from a height and when

it strikes the floor, ground or some toy building or other structure, the cap which has been set in the slot 9 is struck by the striker 13 as the body 5 rides downwardly on the rod 11. The cap is exploded giving a loud report and simultaneously the lug 14 is displaced from engagement with the spring end allowing the spring to uncoil and sweep outwardly in a circumferential motion to topple over toy houses, tents, soldiers and other items that may be in its path.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A toy bomb which includes a body, a spring coiled about the body, a plunger reciprocable in the body, a catch for holding the spring in coiled position about the body and means operated upon advance of the plunger into the body to release the catch and permit the spring to uncoil from the body.

2. A toy bomb which includes a body, a spring coiled about the body, a plunger reciprocable in the body, a catch for holding the spring in coiled position about the body, means operated upon advance of the plunger into the body to release the catch and permit the spring to uncoil from the body, and means operating in unison with the release of the catch to detonate a cap carried by the body.

3. A toy bomb which includes a body having an

axial bore opening through its lead end and a transverse pocket opening through its side and communicating with the bore, an elongated spring coiled about the body between the transverse pocket and the lead end of the body, a plunger slidably axially in the bore, a striker arm extending radially from the plunger through the pocket and a lug on the striker arm for engaging the outermost convolution of the spring and holding it against uncoiling until the plunger moves inwardly relative to the body.

4. A toy bomb which includes a body having an axial bore opening through its lead end and a transverse pocket opening through its side and communicating with the bore, said body having a peripheral groove between the pocket and its lead end in which an elongated spring is adapted to be coiled, a plunger slidably longitudinally in the bore, a striker arm extending radially from the plunger through the pocket and a lug on the striker arm adapted when the plunger is advanced with relation to the body to overhang the groove and the spring coiled therein to hold the spring in such coiled position and when the plunger is retracted to clear the groove and allow the spring to uncoil from the body.
